(57) **CLAIM**

The ornamental design for a hose guide, as shown and described.

DESCRIPTION

FIG. 1 is a front perspective view of a hose guide; FIG. 2 is a front elevation view thereof; FIG. 3 is a rear elevation view thereof; FIG. 4 is a right elevation view thereof; FIG. 5 is a left elevation view thereof; FIG. 6 is a top plan view thereof; and, FIG. 7 is a bottom plan view thereof. The broken lines showing a hose guide are included for the purpose of illustrating environment and form no part of the claimed design.
